UNITED STATES PATENT OFFICE.

JAMES S. CUMING, OF ST. LOUIS, MISSOURI.

DESIGN FOR A PLURAL-SOCKET PLUG.

Application filed January 20, 1922. Serial No. 294. Term of patent 14 years.

To all whom it may concern:

Be it known that I, JAMES S. CUMING, a citizen of the United States, residing at St. Louis, Missouri, have invented a new, original, and ornamental Design for Plural-Socket Plugs, of which the following is a specification, reference being had to the accompanying drawing, forming part thereof.

The figure is a perspective view of a plural socket plug showing the new design.

I claim:

The ornamental design for a plural socket plug, as shown.

In testimony whereof I have hereunto affixed my signature.

JAMES S. CUMING.
